S. S. SONNEBORN,
UNIVERSALLY GRADABLE SUSPENSION INSULATOR,
APPLICATION FILED AUG. 25, 1917.

1,291,218.

Patented Jan. 14, 1919.

UNITED STATES PATENT OFFICE.

SOL S. SONNEBORN, OF BROOKLYN, NEW YORK.

UNIVERSALLY-GRADABLE SUSPENSION-INSULATOR.

1,291,218.

Specification of Letters Patent. Patented Jan. 14, 1919.

Application filed August 25, 1917. Serial No. 188,236.

To all whom it may concern:

Be it known that I, SOL S. SONNEBORN, a citizen of the United States, and a resident of Brooklyn, county of Kings, and State 5 of New York, have invented certain new and useful Improvements in Universally-Gradable Suspension-Insulators, set forth in the following specification.

This invention relates to suspension insulators of the high tension type and particularly to the type built up from a series of insulator units.

It is customary in supporting high tension transmission lines, in accordance with one 15 practice, to employ at a point of support an insulator formed of a string of a plurality of high tension suspension insulator units, connected in series so that the insulating power of each unit will be added to that of 20 each other unit in the string. In practice it has been found to be difficult uniformly to divide the full potential of the line across each insulator unit. This difficulty is partly due to the fact that the normal potential 25 across each insulator is proportional to capacity current rather than to leakage current when the leakage currents are relatively small. The above is on the hypothesis that all the insulator units are identical. What is 30 known as grading has been resorted to more uniformly to distribute and divide the potential across the individual insulator units by varying the electro-static capacity of the various individual insulator units. This 35 method of grading has necessitated that the different insulator units of a string be physically different one from another, giving rise to the disadvantage of non-interchangeability of parts and the necessity of carrying on 40 hand for repairs a number of each of the different distinct insulator units rather than a number of insulator units all alike, any one of which could be used for repair of any one 45 of the insulator units of a string or complete suspension insulator.

Heretofore, in my application for patent Serial No. 147,736, filed Feb. 10, 1917, for adjustable suspension insulator, I have described how I can accomplish grading in a 50 string of identical units by varying the relative positioning of the units in the string and by providing means for this purpose.

The object of the present invention is still further to improve my method of producing 55 grading in a string of identical insulator

units, which I accomplish by the interposition, in various localities of the string, of substantially indestructible parts, such as metallic hoods or canopies, and other forms of arcing members such as disks and members providing radially extending spokes or horns. Either without varying the positioning of the insulator units of the string or with varying the positioning of the units of a string, I effect grading by adjustably positioning such devices as the aforementioned arcing members. The above and further objects of the invention will better be understood by reference to the illustrative embodiment set forth in the following specification 70 and claims, which should be read in connection with the drawings which form a part hereof, and in which the single figure is a vertical elevation, with parts shown in vertical section, of an illustrative embodiment 75 of a suspension insulator in accordance with my invention.

The insulating power of the insulator is provided through the medium of a plurality of any desired number of insulator units T, 80 T' and T'', which are preferably of the type described in detail in my aforementioned co-pending application, in which the shanks 21, 25 and 32 are axially adjustable relatively to the units T, T' and T'' respectively. In 85 addition to the insulator units which are supported in adjustable positions from the cross arm 1 through the medium of a bolt 2, swiveled to the unit T by the bolt 3, I provide one or more radially extensive members 90 of conducting material A, B, C, D. In the illustrative embodiment the members A, B, C, D are all different, but I desire it to be understood that I contemplate the employment of a plurality of any one of the individual forms A, B, C, D, or any combination 95 of the same.

The embodiment A is a hood or canopy of sheet metal, supported by a hub 10, tapped to be adjustably threaded onto the shank of 100 the bolt 2 and locked in adjustable position by the lock nut 11. The embodiment B has a hub 20 tapped to be adjustably threaded on the bolt shank 21 between the units T and T', and locked in position by the lock nut 105 22, and is provided with a plurality of equally spaced radially projecting arms 23, each terminating in an upturned, pointed tip 24. It is suggested that eight arms is an appropriate number.

The member C is merely a disk of sheet metal positioned upon the bolt shank 25 between the units T' and T'' through the medium of two nuts 26 and 27, jamming against 5 opposite faces of the disk.

The member D comprises the hub 30, to which a plurality of radially extending arms 31 are secured in a suitable manner as by riveting. In this embodiment the arms are 10 straight. The hub 30 is suitably threaded for adjustable positioning upon the bolt shank 32 and the jam nut 33 serves to fix its position. The line wire 35, clamped in a suitable clamp 36, is swiveled to the bolt shank 33 through the medium of the fork 15 and bolt 37.

In operation, it is contemplated that records of the altitude above sea-level be made 20 for various positions along a transmission line, and that the spacing of the insulator units and the positioning of the arcing members be determined in accordance with these altitude measurements, and in accordance with any and all other special conditions 25 which have an effect upon grading. The arcing members, when they are in the form of the hood A, serve also the function of an efficient weather shield, and they may all be employed for the function of distributing 30 electro-static stress, which is particularly true of the hood and disk types shown in the embodiments A and C. All of the arcing members are serviceable in adjusting the string so that the arcing values both for 35 rainy and dry weather may be made equal.

What is claimed and what is desired to be secured by United States Letters Patent is:—

1. A high-potential insulator adjustable 40 in its electrical functions, comprising a plurality of insulator-units, connected in series; and one or more arcing members of conducting material bodily adjustably mounted coaxially of said series of insulator-units.
2. A high-potential insulator adjustable 45 in its electrical functions, comprising a series of identical insulator-units having axially adjustable connecting means; and one or more arcing members of conducting material

adjustably mounted coaxially of said series 50 of insulator-units.

3. A high-potential insulator adjustable in its electrical functions, comprising a series of insulator-units having end terminals; and an arcing member bodily adjustably mounted 55 on the end terminals of said series.

4. A high-potential insulator adjustable in its electrical functions, comprising a series of insulator-units having end terminals; one or more arcing members of conducting ma- 60 terial each bodily adjustably mounted between two adjacent insulator-units; and an arcing member bodily adjustably mounted on the end terminals of said series.

5. A high-potential insulator comprising 65 a series of insulator units; a plurality of threaded connecting bolts mutually connecting said units between a support and a line conductor; and one or more arcing members having hubs in threaded adjustable engage- 70 ment with said bolts.

6. A high-potential insulator comprising a series of insulator units; a plurality of threaded connecting bolts mutually connecting said units between a support and a 75 line conductor; a metallic hood adjustably mounted on one of said bolts between said support and an insulator unit; and one or more arcing members having hubs in threaded adjustable engagement with said 80 bolts.

7. In combination in a high-potential insulator chain, a plurality of insulator units having one or more axially adjustable connecting means; and a laterally extensive conducting member bodily axially adjustable and mounted on a said connecting means, 85 whereby a ready adjustment of capacity may be effected.

8. A high-potential insulator having un- 90 symmetrical metallic terminals in combination with a bodily axially adjustable laterally extensive conducting member in electrical connection with one of said terminals of said insulator, whereby capacity may be 95 adjustably varied.

Aug. 14, 1917.

SOL. S. SONNEBORN.
